UNITED STATES PATENT OFFICE.

WILLIAM H. LUTTON, OF JERSEY CITY, NEW JERSEY.

GREENHOUSE.

1,210,502.

Specification of Letters Patent.

Patented Jan. 2, 1917.

Application filed February 3, 1914. Serial No. 816,193.

To all whom it may concern:

Be it known that I, WILLIAM H. LUTTON, a citizen of the United States, residing in the city of Jersey City, county of Hudson, 5 and State of New Jersey, have invented certain new and useful Improvements in Greenhouses, of which the following is a specification.

My invention relates to improved greenhouse construction having for its purpose the admission of a maximum of light together with simplicity of design and certain other features of advantage, as will further appear.

15 The subject-matter of the present application is an improvement upon the construction illustrated in my prior Patent No. 902,155, dated October 27, 1908.

In the accompanying drawings which 20 form a part of this specification, Figure 1 is a perspective view partly in section showing my improved construction; Fig. 2 is a transverse sectional view on an enlarged scale of the foundation and a portion of the 25 superimposed structure; Fig. 3 is a transverse sectional view on line III—III of Fig. 1, and Fig. 4 is a transverse sectional view on line IV—IV of Fig. 1.

Referring to the drawings in detail, the 30 numeral 1 designates a foundation wall which may be of concrete, brick, or any other suitable construction. Upon this wall is mounted a sill 2 having depending flanges 3 and 4. A gutter 5 is mounted upon the 35 depressed offset surface 6 of the wall, the upper level of the flange of the gutter thus lying below the level of the sill. Drainage is provided through the agency of an inclined leader 7 passing through the wall to the 40 interior of the greenhouse and there connecting with a vertical leader 8. This construction of gutter and drain is exceedingly advantageous; first, for the reason that the depressing of the gutter below the level of 45 the sill permits snow to fill the gutter in winter time without banking up over the glass in the side of the greenhouse and thus obstructing the light; and, second, because the use of an interior drain prevents freezing and consequent clogging and overflow 50 of the drain.

The glazed portion of the greenhouse is carried by curved rafters 9 mounted upon the sill by means of brackets 10. These rafters are continuous, running from the sill 55 to the portion 11, where they are curved, and then extending in an inclined direction to the ridge, to which they are joined in a well known manner. Each rafter supports a correspondingly curved angle iron 12 by 60 means of a rafter back or capping 13 of M-section, which is preferably constructed of copper or some other comparatively soft metal. The use of this back or capping compensates for any inequalities in the curvature of the rafter and its associated angle. 65 The angle itself is preferably constructed of galvanized iron and has mounted in it a core 14 which may be constructed of cypress wood or other suitable material. 70 This core is essentially of inverted T-section, as clearly shown in Figs. 3 and 4, having portions adapted to seat against the inner surfaces of the legs of the angle, the opposite sides of these portions being 75 beveled or chamfered and affording a support for the glass 15, adjacent panes being separated by the shoulder 16, which may also carry suitable means, not shown, for holding the glass in place. The legs of the 80 angle extend somewhat beyond the surfaces of the core which seat upon them, thus forming gutters 17 adapted to carry the water of condensation down to the sill and thus preventing any drip from the roof due to 85 the condensation of moisture within the house.

It will be observed that this construction affords a firm and yet cushioned seating for the glass, resulting from the use 90 of the wood core provided with the chamfered glass-bedding surfaces. Because of the great strength of this construction, the rafters may be spaced at considerable intervals to form bays, as shown in Fig. 1. 95 The adjacent rafters are connected by horizontal angle irons 18 which stiffen the entire structure, particularly taking up wind stresses upon the ends of the house. These horizontal, longitudinal angles also act as 100 supports for the intermediate vertical angles 19 which are identical with the angles 12

already described and which are provided with cores 20 corresponding to cores 14, the only difference being that these angles are not supported by rafters and thus no rafter back or capping is associated with them. The number of these intermediate vertical angles 19 in a bay, that is, between two rafters, is dependent upon the width of the bay formed by adjacent rafters and by the width of the panes of glass. They are not primarily required for structural support, since the load is principally carried by the rafters. This construction is one which entirely avoids the necessity for the use of posts to support the roof, since the strength of the rafters disposed on edge is adequate to support this load. Furthermore, a maximum of light is admitted to the interior of the house owing to the use of angle irons, the legs of which are disposed at 45 degrees to the plane of the glass. The V-construction resulting from this arrangement of the angles permits the rays of light entering the house to merge, as it were, after passing the apex of the angles, so that no appreciable shadow is noticeable at any substantial distance away from the angles. The use of rafters formed of unitary bars bent on edge and disposed at right angles to the glass also causes a minimum interference with the light and promotes the substantially uniform illumination of the interior of the house, and consequently provides a maximum glass area, an area which is substantially much larger in proportion to the superficial area of the house than that afforded by any other construction of which I am aware.

While I have illustrated and described only one specific embodiment of my invention, I realize that it is susceptible of wide application and I do not desire to be limited to the precise construction illustrated and described.

Having thus described my invention, I claim:

1. In greenhouse construction, a curved rafter comprising a flat unitary metal bar arranged edgewise with respect to the glazed medium, an angle iron for supporting the glazed medium having its legs disposed at 45 degrees to the plane of the said medium, and relatively yielding means for supporting said angle from said rafter.

2. In greenhouse construction, a rafter comprising a flat unitary metal bar arranged edgewise with respect to the glazed medium, an angle for supporting the glazed medium having its legs disposed at 45 degrees to the plane of the said medium, and relatively yielding means for supporting said angle from said rafter comprising a metal back-ing strip of M-section.

3. In greenhouse construction, a rafter

comprising a unitary metal bar arranged edgewise with respect to the glazed medium, and an angle for supporting the glazed medium having its legs disposed at 45 degrees to the plane of said medium, means for supporting said angle from said rafter, and a core mounted within the angle forming a seat for the glazing member.

4. In greenhouse construction, a rafter comprising a unitary metal bar arranged edgewise with respect to the glazed medium, and an angle for supporting the glazed medium having its legs disposed at 45 degrees to the plane of said medium, means for supporting said angle from said rafter, and a core mounted within the angle forming a seat for the glazing member, the legs of the angle extending beyond said core to form condensation gutters between said core and said legs.

5. In greenhouse construction, a rafter comprising a unitary metal bar arranged edgewise with respect to the glazed medium, and an angle for supporting the glazed medium having its legs disposed at 45 degrees to the plane of said medium, means for supporting said angle from said rafter, and a core mounted within the angle forming a seat for the glazing member, said core having a shoulder adapted to project between adjacent panes of glass and space the same.

6. In greenhouse construction, a foundation having an offset depressed portion, a sill mounted on said foundation, a glazed side wall mounted on said sill, a gutter mounted on said depressed portion below the level of said sill exterior to said wall, and a drain leading from the gutter through said foundation to the inside face thereof.

7. In greenhouse construction, an angle for supporting the glazed medium having its legs disposed at 45 degrees to the plane of said medium, and a core mounted within the angle forming a seat for the glazed medium, the legs of the angle forming a joint with said core and extending therebeyond to form condensation gutters between said core and said legs.

8. In greenhouse construction, a rafter comprising a unitary metal bar, a retaining means for a glazed medium, said rafter constituting a rigid support for said retaining means, said retaining means being of greater breadth than said rafter, and a member having divergent sides interposed between said rafter and said retaining means.

9. In greenhouse construction, a rafter comprising a unitary metal bar, an angle member extending therealong and supported thereby, and a wooden core held between the arms of said angle member, said core being adapted to hold the glazed medium.

10. In greenhouse construction, a narrow metal rafter having its edge disposed toward the glazed medium, a substantially resilient member of greater breadth than
5 said rafter for supporting the glazed medium, a member having diverging sides for holding said last-mentioned member, and

yielding means between said rafter and said member provided with converging sides.

WILLIAM H. LUTTON.
